FIG.1

FIG.2

FIG.3

FIG.4

FIGURE 1 illustrates a side elevation of a base for supporting a toy figure showing my new design;

FIGURE 2 illustrates a plan view of the top of said base;

FIGURE 3 illustrates a perspective view of the top of said base; and

FIGURE 4 illustrates a perspective view of the underside of said base.

The characteristic feature of my design resides in the hemispherical configuration in combination with a diametrical slot on the flat upper face flanked by depressions in the particular configuration shown.

I claim:

The ornamental design for a base for supporting a toy figure or the like, as shown and described.
